DESIGN FOR A TOY AUTOMOBILE

James E. Gibson, Jr., High Point, N. C.

Application January 25, 1945, Serial No. 117,599

Term of patent 3½ years

(Cl. D34—15)

To all whom it may concern:

Be it known that I, James E. Gibson, Jr., a citizen of the United States, residing at High Point, county of Guilford and State of North Carolina, have invented a new, original, and ornamental Design for Toy Automobile, of which the following is a specification, reference being had to the accompanying drawing, forming a part thereof.

Figure 1 is a side elevation of a toy automobile embodying my new design;

Figure 2 is a bottom plan view thereof;

Figure 3 is a front elevational view of same;
Figure 4 is a rear elevational view thereof;

Figure 5 is a vertical transverse sectional view thereof substantially as seen on line 5—5 of Figure 1; and

Figure 6 is a vertical longitudinal sectional view thereof substantially as seen on line 6—6 of Figure 2.

I claim:

The ornamental design for a toy automobile, as shown.

JAMES E. GIBSON, JR.
